US0D1094733S

(12) **United States Design Patent** (10) **Patent No.:** **US D1,094,733 S**
(45) **Date of Patent:** **** Sep. 23, 2025**

(54) **NIPPLE SHIELD**

(71) Applicant: **Shenzhen Lute Jiacheng Supply Chain Management Co., Ltd.**, Shenzhen (CN)

(72) Inventor: **Yang Yang**, Shenzhen (CN)

(73) Assignee: **Shenzhen Lute Jiacheng Supply Chain Management Co., Ltd.**, Shenzhen (CN)

(**) Term: **15 Years**

(21) Appl. No.: **29/944,997**

(22) Filed: **May 31, 2024**

(51) **LOC (15) Cl.** **24-04**

(52) **U.S. Cl.**

USPC **D24/190**

(58) **Field of Classification Search**
